ATTORNEYS.

UNITED STATES PATENT OFFICE.

LEROY REIMER, OF BROOKLYN, NEW YORK, ASSIGNOR OF ONE-HALF TO JOHN M. LEHMAN, OF BROOKLYN, NEW YORK.

COLLAPSIBLE HANGING SEAT.

Application filed July 25, 1924. Serial No. 728,106.

To all whom it may concern:

Be it known that I, LEROY REIMER, a citizen of the United States, residing at Brooklyn, county of Kings, and State of New York, have invented certain new and useful Improvements in Collapsible Hanging Seats, fully described and represented in the following specification, and the accompanying drawings, forming a part of the same.

This invention relates to certain improvements in collapsible and detachable seats which are designed for use in bathtubs and the like, or lunch counters and other situations where removable, foldable or collapsible seats may be desired.

A special object of the invention is to produce such a seat which is easily and quickly folded up and removable from the place in which it is used, and which is adjustable so that it can be used in bathtubs or like situations where the incline of the wall of the tub varies, the seat being so arranged as to be substantially horizontal as used with the tub walls, the incline of which varies considerably, as, for instance, the end and side walls of a bathtub of the usual configuration.

A further object of the invention is to provide such a seat of simple form and of few parts so as to be cheap to manufacture but at the same time durable and which when in position forms a rigid support.

With these and other objects not specifically referred to, the invention consists in certain novel parts, arrangements and combinations which will be described in connection with the accompanying drawings, and the novel features thereof pointed out in the claims hereunto annexed.

In these drawings,—

Figure 1 is a side view of the improved seat showing the seat applied to the end of a bathtub where the slant of the wall is considerable, a bathtub wall being shown in section;

Figure 2 is a similar view showing the seat arranged to hang on the side wall of the tub where the slant of the wall is less than that shown in Fig. 1;

Figure 3 is a bottom view of the improved device removed from the tub;

Figure 4 is a side view of the device showing the parts folded together, and

Figure 5 is a bottom view, the different

parts being broken away, of a modified construction which may be employed.

Referring now to these drawings, the improved seat has been illustrated as used in a bathtub. It will be understood, however, that the seat is capable of and has been designed for use in other relations, as, for instance, it could be hung over the edge of a lunch counter or similar situations, and the invention is not to be restricted to a bathtub use.

In the preferred embodiment of the invention, the improved device will include a seat 1 which may be of any desirable configuration of any suitable material, such as a circular wooden disc. This seat has secured thereto a hanger support by which the seat may be hung or suspended in the place desired. This hanger support may be of various configurations and secured to the seat in various ways. Referring to the construction shown in Figs. 1 to 4, this hanger support includes a pair of bars 2, 3 which are curved at their upper ends to form hooks 4 which are united by a cross-bar 5, these hooks and the bar 5 in the best constructions being covered with some soft material, such as rubber, indicated by the numeral 6, to prevent injury to the surface with which the seat is used.

This hanger support is pivotally connected with the seat, and this pivotal connection may be provided in various ways. As shown in Fig. 3, there are secured to the bottom of the seat, as by screws 7, a pair of brackets 8, 9 having inturned ends 10 which form bearings for the hanger rods 2, 3. These hanger rods 2, 3 are bent inwardly, as indicated at 11, to engage the bearings 10 and are then bent downwardly to form legs 12 which are provided with upwardly turned ends forming open hooks 13.

Also pivotally secured to the seat is a brace, and this brace, in constructions embodying the invention, will be so formed and arranged that it will have two points of connection with the hooked ends of the hanger support so that the brace will extend at different angles relatively to the seat, so that the seat may be adjusted to walls, as, for instance, the walls of a bathtub, which vary in inclination and yet remain horizontal when in adjusted position, the brace being positively connected. This brace may vary somewhat in construction and in the method

of attaching it to the seat. As shown, however, the brace is in the form of a rectangle made of rod metal of suitable strength, this rectangle having ends 14, 15 and sides 16. 5 The end 14 of the rectangle is pivotally attached to the bottom of the seat by taking bearing in the inturned ends 17 of brackets 18. The lower end 15 of this brace may be covered with rubber or other pliable material 17' and is intended for attachment to the hooks 13 of the hanger support where the device is used with a wall but slightly off vertical, as shown in Fig. 2. Pivotally attached to the brace 16 is an auxiliary brace 10 frame comprising side arms 19, 20 and a cross piece 21, this piece 21 being preferably integral with the arms 19, 20. These arms 19, 20 are inturned at their inner ends to have a pivotal engagement with the end member 15 of the main brace member. The cross piece 21 of this auxiliary brace is arranged for engagement with the hooks 13 of the hanger support, this adjustment being used where the wall with which the device 15 is employed is sharply inclined, as shown in Fig. 1.

With this construction a very simple, effective and rigid seat is provided, which with but few parts, is cheap to manufacture, 20 and which is easily adjusted to the desired position, and where desired the whole device may be removed and collapsed into small compass.

In Fig. 5 is illustrated a slight modification 25 in the means for pivotally connecting the hanger support to the seat. As there shown, there is provided a U shaped rod 22 having outwardly extending ends 23, and the arms 2, 3 of the hanger support are loosely looped 30 around these ends, as indicated at 24, a somewhat simpler construction being provided by this modification, which may be used under some circumstances if desired.

While the invention has been shown and 35 described in its preferred form, it will be understood that certain changes and variations may be made in the specific construction illustrated without departing from the invention, as defined in the appended claims.

50 What I claim is:

1. In a device of the character described, 35 the combination with a seat of a hanger support therefor, including a pair of spaced members hooked at their outer ends for suspending the device and pivotally connected

with the seat, securing devices on the members, an adjustable brace pivotally secured to the seat, and a second brace pivotally secured to the first brace, both of said braces being provided with means for detachably connecting either of them to the securing devices on the supporting members.

2. In a device of the character described, the combination with a seat of a hanger support therefor, including a pair of spaced rods, hooked shaped at their outer ends, for suspending the device and pivotally connected with the seat, said rods having hooked inner ends, a brace frame pivotally connected with the seat and including side members and a cross member for removable engagement with the hooked inner ends of the hanger support, and a second brace member pivotally connected with the main brace and provided with means for removably engaging it with the hooked inner ends of the hanger support.

3. In a device of the character described, the combination with a seat of a hanger support therefor, including a pair of spaced side bars, hooked shaped at their outer ends, for suspending the device and pivotally connected with the seat, said bars having hooks on their inner ends, a brace frame pivotally connected with the seat and including side members and a cross member for removable engagement with the hooked inner ends of the hanger support, and a second brace frame pivotally connected with an end of the main frame and provided with cross pieces for engaging the hooked inner ends of the hanger support.

4. In a device of the character described, the combination with a seat of a hanger support therefor, including a pair of spaced rods, hooked shaped at their outer ends, for suspending the device and provided with hooks at their inner ends, a bar connected with the seat provided with bearing portions, said spaced rods of the hanger support being bent upon themselves to form a loop for engagement with the bearing portions of the bar, and a brace pivotally connected with the seat and having brace members provided with spaced means for removably securing the brace to the hanger support at different angles relatively to the seat.

In testimony whereof, I have hereunto set my hand.

LEROY REIMER.
